UNITED STATES PATENT OFFICE.

HENRY A. ARMSTRONG, OF BROOKLYN, NEW YORK, ASSIGNOR TO MERGENTHALER LINOTYPE COMPANY, A CORPORATION OF NEW YORK.

TYPOGRAPHICAL MACHINE.

1,101,383.

Specification of Letters Patent. Patented June 23, 1914.

Application filed July 12, 1913. Serial No. 778,668.

To all whom it may concern:

Be it known that I, HENRY A. ARMSTRONG, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line together with spacers, the composed line transferred to the face of a mold, the mold filled with 20 molten metal to form a slug or linotype against the matrices which produce the type characters thereon, and the matrices and spacers thereafter returned through distributing mechanism to the magazine from 25 which they started. More particularly, it relates to the means whereby the spacers are delivered to the assembler in the course of composition, and is designed to prevent their accumulation and clogging in the spacer 30 magazine or chute, as will hereafter appear more fully from the detailed description thereof.

In the accompanying drawings, I have shown my invention in preferred form and 35 by way of example, and as applied to the spacer-releasing means of a linotype machine. Obviously, many changes and variations may be made therein, and in its mode of application, which will still be comprised 40 within its spirit. For instance, the improvements may be similarly applied to other forms of typographical machines, which handle type or dies instead of matrices, or they may be adapted to other forms of 45 espacements, which control any kind of line elements, such as matrices, types and dies as well as spacers. Generally speaking, I desire it to be understood that I do not limit myself to any specific form or embodiment, 50 except in so far as such limitations are specified in the claims.

Referring to the drawings: Figure 1 is a skeleton perspective view of the spacer-releasing mechanism, etc., having my invention applied thereto; Fig. 2 is a side view of

a portion thereof; Fig. 3 is a similar view, showing the parts in different position; and Fig. 4 is a sectional detail on the line 4-4 of Fig. 3.

As in the Mergenthaler patent before 60 mentioned, or as in the ordinary commercial linotype machine, the matrices X and spacers Y are delivered one by one into the assembler A, between the yielding resistant A' therein and the rotating star wheel B, 65 whereby the line is advanced and compacted. The spacers Y are stored in the magazine C and descend therefrom through the chute C' to the point of composition. The release of the spacer from the magazine is controlled by the key D, the power-operated keyboard mechanism D', the reed D², and the lever E. The reciprocable escapement pawls F are carried by the pivoted frame F', engaging at F² with one end of the lever 70 E, the connection F² being preferably a loose one, such as a slot, to permit the movement of the lever E with reference thereto, in the event that for any reason the frame F' is 75 not permitted to descend.

Fig. 1 shows the parts in normal position, with the pawls F elevated and in front of the outermost spacer. When the key D is operated, the first effect is to lower the inner end of the lever E, whereby the frame F' and pawls F are also lowered, to permit the pawls to engage beneath the ears of the outermost spacer, as shown in Fig. 2. The end of the lever E then moves upwardly, raising the frame F' and pawls F to free 90 the spacer, which descends through the chute C' in front of the star wheel B, as shown in Fig. 3. The parts so far described are or may be of any desired form or construction. which in itself constitutes no part of my 95 present invention.

In the use of these machines, it sometimes happens that the spacers are not delivered to the assembler with certainty, and consequently they stick or clog either in the 100 magazine C or chute C', and particularly when the operator is unaware of the difficulty and continues to operate the key D. In such circumstances it becomes necessary to arrest the mechanism to clear the parts, involving not only inconvenience and loss of time, but also the liability to breakage of the thin spacers during their removal, and even the cutting of the operator's fingers by their sharp edges. It is a principal pur- 110

pose of my invention to obviate these difficulties, and to this end I have provided means whereby the release of a second spacer is prevented unless the previous one has 5 passed into the line and the chute is therefore empty. To accomplish these results, I provide the rocking frame F' with a depending arm or slide G, suitably guided upon the stationary frame, and on the slide 10 mount the pivoted trigger H, normally forced upward by the spring H', against the stop finger H². Below the slide is located the stop arm J, pivotally connected to the stationary frame and urged inward by 15 the spring J' to bring the pin J² at its upper end into engagement with the trigger H. Also pivotally mounted on the framework, and preferably in the axis of the arm J, is the depending frame K', formed at its lower 20 end with the feeler K, which projects into the chute C', in proximity to the two beveled edges C², along which the ears of the spacer travel, as it leaves the chute and passes in front of the star wheel B.

25 The arrangement of the parts is such that as the star wheel moves the spacer forwardly, the latter engages the feeler K and rocks the frame K' about its axis. The stop arm J is provided with the inwardly projecting pin K² located in position to be engaged by the frame K', when the feeler is moved by the passage of the spacer from the chute, and thereby to swing the stop arm J about its axis. This loose connection 30 also permits a certain amount of lost motion without affecting the arm J, and therefore allows the feeler K to rest against and guide the lower portion of the spacer, as it passes through the chute and before 35 it has descended to its full extent.

40 The operation of my improvements will now be clearly understood. The normal position of the parts is that indicated in Fig. 1, with the frame F' elevated, the arm J in its outer position and with its pin J² engaging the trigger H, and the feeler K in its innermost position in the chute C'. Referring to Fig. 2, the frame F' and slide G then descend and carry the trigger H out of 45 engagement with the pin J², whereupon the arm J is moved inwardly by the spring J' until it contacts with the slide G. The frame F' and slide G next ascend, as shown in Fig. 3, whereupon the arm J moves farther inwardly and its pin J² passes over the trigger H. This brings the upper end of the arm J beneath the slide G and thus prevents the downward movement of the frame F', and consequently the further actuation 50 of the escapement, until the arm J be moved outwardly again to its normal position. This latter operation is effected, as indicated by dotted lines in Fig. 3, by the lateral movement of the released spacer, caused by the 55 engagement of its ears with the bevels C²,

thus swinging the guide K outwardly, and through the engagement of the frame K' with the pin K², moving the stop arm J to its outer or inoperative position. In other words, if the spacer passes entirely through 70 and clears the chute C', the escapement is unlocked by the outward movement of the arm J, and the trigger H moves upwardly, and again engages the pin J², as shown in Fig. 1. If, however, for any reason, the 75 released spacer is held in the chute C', the feeler K is not moved, and consequently the arm J remains in its inward position and prevents the further actuation of the escapement, until the offending spacer be removed. It will be seen that in this way I prevent 80 the piling up or clogging of released spacers in the magazine or chute.

As previously stated, I have shown my invention only in preferred form and by way 85 of example, and as applied to a linotype machine, and obviously many modifications and alterations therein, and in its mode of application, will suggest themselves to those skilled in the art, without departure from 90 its scope.

Having thus described my invention, its construction and mode of operation, what I claim and desire to secure by Letters Patent of the United States, is as follows: 95

1. In a typographical machine, the combination of releasing devices for line elements, the stop J to lock said devices against operation, the trigger H to hold said stop in inoperative position, means to trip the trigger H, and the feeler K to restore the stop to inoperative position. 100

2. In a typographical machine, the combination of releasing devices for line elements, the stop J to lock said devices against operation, the trigger H to hold said stop in inoperative position, the slide G to actuate the trigger H, and the feeler K to restore the stop to inoperative position. 105

3. In a typographical machine, the combination of releasing devices for line elements, a stop to lock said devices against operation, means to hold the stop in inoperative position and to permit it to move to operative position, and automatic means 110 connected to the stop and controlled by a released line element to restore it to inoperative position. 115

4. In a typographical machine comprising assembling mechanism, the combination of releasing devices for line elements, a stop to lock said devices against operation, and unlocking means connected to the stop, the said means being actuated by the delivery 120 of a released element to the assembling mechanism. 125

5. In a typographical machine comprising assembling mechanism, the combination of releasing devices for line elements, a stop to lock said devices against operation, and 130

means connected to the stop to move it to inoperative position, the said means being actuated by the delivery of a released element to the assembling mechanism.

5 6. In a typographical machine comprising assembling mechanism, the combination of releasing devices for line elements, means to lock said devices against operation, and means actuated by the delivery of a released element to the assembling mechanism 10 to unlock said devices.

7. In a typographical machine, the combination of releasing devices for line elements, and means for locking said devices 15 against operation and actuated by a released element to unlock said devices.

8. In a typographical machine comprising assembling mechanism, the combination of releasing devices for line elements, and 20 means to lock said devices against operation and arranged to be moved to unlocking position by the delivery of a released element to the assembling mechanism.

9. In a typographical machine comprising 25 assembling mechanism, the combination of releasing devices for line elements, and means to prevent the further operation of said devices until a previously released element is delivered to the assembling mechanism.

30 10. In a typographical machine comprising assembling mechanism, the combination of releasing devices for line elements, and means to lock said devices against operation when an element is released and to 35 unlock them when the released element is delivered to the assembling mechanism.

11. In a typographical machine comprising 40 assembling mechanism, the combination of devices for releasing line elements, means

controlled by the actuation of said devices to lock them against further operation, and means controlled by the delivery of a released element to the assembling mechanism to unlock said devices.

45

12. In a linotype machine, the combination of the spacer magazine, the spacer escapement and actuating means therefor, the spacer chute, and means to lock the escapement against actuation until a released 50 spacer has passed from the chute.

13. In a linotype machine, the combination of the spacer magazine, the spacer escapement and actuating means therefor, the spacer chute, a stop to lock the escapement 55 against operation, and means to remove the stop when a released spacer passes from the chute.

14. In a linotype machine, the combination of the spacer magazine, the spacer escapement and actuating means therefor, the spacer chute C' formed with the bevels C², a stop to lock the escapement against operation, and means to remove the stop actuated by a released spacer passing along the 60 bevels C².

15. In a linotype machine, the combination of the spacer magazine C, the spacer escapement and actuating means therefor, the spacer chute C', the stop J to lock the escapement against action, and the feeler K to remove the stop when a released spacer 70 passes from the chute.

In testimony whereof I have affixed my signature in presence of two witnesses.

HENRY A. ARMSTRONG.
